United States Patent Office.

JOHN V. JENKINS, OF MANCHESTER, MICHIGAN, ASSIGNOR TO RICHARD B. WALKER AND LEWIS MILLER, OF AKRON, OHIO.

Letters Patent No. 66,966, dated July 23, 1867.

MACHINE FOR SHEARING SHEEP.

The Schedule referred to in these Letters Patent and making part of the same.

TO ALL WHOM IT MAY CONCERN:

Be it known that I, JOHN V. JENKINS, of Manchester, in the county of Washtenaw, and State of Michigan, have invented certain new and useful improvements in Machines for Shearing Sheep; and I do hereby declare the following to be a full, clear, and exact description of the same, reference being had to the accompanying drawings, making a part of this specification, in which—

Figure 1 represents a perspective view of the machine complete, and as it appears when ready for use.

Figure 2 represents a section through the same.

Figures 3 and 4 represent details of the machine, which will be hereafter more specially referred to.

Similar letters of reference where they occur in the separate figures denote like parts of the machine in all the drawings.

My invention consists, first, in a jointed wrist for communicating motion to the shears or cutters, so arranged that the wrist-shaft can be placed at any angle with the vibrating beam or sway-bar and still accommodate itself to the connecting-shaft. My invention further consists in a presser that can be brought against the knife or cutter at the will of the operator, or be released at pleasure, and without stopping the action of the shears, the object being to hold the cutter to the fingers with more or less force, as may be required. My invention further consists in the manner of connecting the cutters or knife-blades to the vibrating sway-bar, so that they can be readily detached for being sharpened and as readily replaced again.

To enable others skilled in the art to make and use my invention, I will proceed to describe the same with reference to the drawings.

A represents a base or stand, on which a column, B, is placed for supporting a main drive-wheel, C, and pulley or belt-wheel, D. This column, above the point where the drive-wheel is hung, may be bent or turned down into a horizontal, or nearly so, position, to form an extended or extension-arm, E, for supporting the working and driving parts of the machine. On the outer end of the extension-arm E, there is hung a pulley, F, around which, and around the main driving-pulley D, passes an endless belt or band, G. Connected with (or in the same piece with it) the pulley F there is a second pulley, H, the shaft *a* supporting both. The pulleys F H, shaft *a*, and guard I, and bail J are all connected to a sleeve or socket, *b*, that fits over and can swing freely on the end of the extended arm E. The sleeve or socket is held on to the arm by the belt G, and the belt is properly strained by the nut *c*, which works on a screw-thread on the arm E and bears against the sleeve or socket *b*, and thus holds it at the adjusted distance to properly tighten the belt. The guard I is fast on or a part of the head, sleeve, or socket *b*, and furnishes one of the bearings for the shaft *a*, and may furnish both of its bearings, though one can be in the head proper. To the bail J is suspended or attached a screw-rod, K, having a thumb-nut, *d*, upon it below the bail. This rod may be run up or down on or in the bail, and when properly adjusted the thumb-nut *d* is run up against the bail to hold it. The other end of the screw-rod K carries or supports a bearing-block, L, one end of which, *e*, forms a bearing for a shaft, *f*, (fig. 2,) which passes through the block L. The other end of said block L forms a bell-shaped shield, *g*, for a toggle or universal joint to work in, as will be hereafter explained. On the central portion of the shaft *f* there is fastened a pulley, *h*, around which, and around the pulley H on the shaft *a*, an endless belt or band, M, passes, and which turns or gives motion to said shaft *f*. On one of the extreme ends of the shaft *f* there is a fly or balance-wheel, N, to give steadiness to its motion, and the other end carries a bail, *i*, united by pins to a disk, hub, or plate, *m*, to which latter is also similarly attached at diametrically opposite points another rod, *j*, thus forming a universal joint between the rods K *j*; and providing means for carrying the power necessary to drive the shears past said joint, and shielding or protecting said joint, so that it may not catch in or wind up the fleece or wool. The outer end of the rod *j* has a bail, *n*, upon it, which is pivoted to the disk, plate, or hub *m*, and to this plate or hub, at diametrically opposite points, is similarly pivoted a bail, *r*, that is on the wrist-shaft *s*, thus making a universal joint between the shafts *j* and *s*, and which joint, for reasons above stated, is shielded or guarded by the bell-shaped guard *k*. The guard or shield not only serves as a protection to the universal joint, and a box or bearing for the wrist-shaft *s*, but has also cast or wrought on to it arms or lugs, *t t*, for supporting and forming a pivoted connection with the shear-stock or plate *l*, and in line with this pivoted connection is the wrist or eccentric *u* on the

wrist-shaft *a*. This eccentric *a* works in the forked or recessed end *v* of a sway-bar, *p*, that is pivoted to the shear-stock *l* at and by the screw-pin *w*, so that it may vibrate about said pivoted point. The front part of the sway-bar *p* is forked, and pointed, with points turning downward, and these points take respectively into holes made to receive them in the cutting-blades *x x*. The points on the sway-bar are all that hold the cutters to the machine, and by releasing the sway-bar, (as will now be explained,) these cutters can be slipped into or out of place in a moment. The upper portion *q* of the shear-stock is pivoted at *y* to the under portion *l*, and the screw pivot-pin *w* passes up through said upper shear-stock *q*, and has a nut, *z*, upon it fitting in a depression in said upper stock, which holds the two parts of the shear-stock together. Underneath the depression in the upper stock there is a corresponding downward projection, *1*, and against the under side of this projection a thumb-nut, *2*, on the screw-pin *w*, bears to keep it from going too low. Between the screw-pin *w* and the pivoted point *y* there is arranged in the upper shear-stock a stud or pin, *3*, which bears against the sway-bar *p*, and the head of this stud is attached to a screw, *4*, by which it may be raised or lowered at pleasure, to increase or diminish its pressure upon the sway-bar.

The operator grasps the shears around and about the point of the screw-pin *w*, the curl *5* of the upper stock *l* receiving the rear portion of his hand, and thus holding the shears the power to drive them is behind his hand, or rather the mechanism to drive them is behind his hand, and the cutters in front of it. By closing his hand on the upper stock, or drawing it towards the under one, the stud *3* is pressed upon the sway-bar and forces the blades *x x* more closely to the fingers *6*, the amount of pressure or force he can exert being limited by the screw *w* and the thumb-nut *2*, which latter can be adjusted or turned from the outside of the stocks. But the operator can thus at will apply more or less pressure upon the cutters by simply tightening or releasing his grasp upon the stocks. The joint at *t*, in line with the wrist or eccentric *a*, enables the shears to bend and play upon it to a great extent upward and backward without cramping or binding the wrist on the sway-bar or checking its driving motion.

Having thus fully described my invention, what I claim therein as new, and desire to secure by Letters Patent, is, first—

The jointed wrist, so arranged that the wrist-shaft can be placed at any angle from the vibrating-team or sway-bar, and accommodate itself to the connecting-shaft without binding, cramping, or impeding the motion of the sway-bar or cutters, substantially as described.

I also claim a presser, so arranged that the operator can at pleasure, and whilst the cutters are in motion, apply pressure upon said cutters to hold them to the fingers or release the pressure, as occasion may require, substantially as described.

I also claim the holding or uniting of the cutters to the sway-bar by means of holes in the former and points on the latter, to allow the cutters to be readily removed for sharpening, and replaced, substantially as described.

JOHN V. JENKINS.
